[57] CLAIM

The ornamental design for a circular cutting blade, as shown and described.

DESCRIPTION

FIG. 1 is a front elevational view of the circular cutting blade showing our new design;

FIG. 2 is a side view thereof, the opposite side view being identical thereof;

FIG. 3 is a rear elevational view of the circular cutting blade shown in FIG. 1; and,

FIG. 4 is a cross-sectional view thereof, taken in the direction of line 4—4 of FIG. 1.

The broken line illustration of the central aperture is for illustrative purposes only and forms no part of the claimed design.
